STOP MOTION FOR BRAIDING MACHINES

John F. Schenck, Sr., Lawndale, and Paul S. Monty, Charlotte, N. C.; said Monty assignor to said Schenck

Application December 8, 1933, Serial No. 701,500

23 Claims. (Cl. 96—19)

This invention relates to a stop motion for a braiding machine of the type shown in Patent Number 1,765,117 of June 17, 1930, in which one of the inventors of the present mechanism is a joint inventor.

It is an object of this invention to provide a stop motion for the type of braiding machine shown in said patent which will stop the operation of the machine when one of the strands being fed to the braiding mechanism becomes parted or too slack, said stop motion having means which are operable to stop the machine regardless of its direction of rotation.

It is a further object of this invention to provide a stop motion for a braiding machine which is operable upon parting of a strand to automatically stop the machine and which embodies means held in elevated position by the strands being braided, said means being adapted to fall upon parting of a strand to in turn operate other means, which in turn are allowed to fall by gravity to engage a normally stationary member to stop the machine, said stationary member being movable to stop the machine regardless of the direction of rotation of the machine.

Some of the objects of the invention having been stated, the details of the apparatus will appear more fully when taken in connection with the accompanying drawings, in which—

Figure 1 is a side elevation partly in section, of a braiding machine with my stop motion attached thereto;

Figure 2 is a top plan view of the strand guiding members with parts omitted, and showing diagrammatically the path of travel of the several fliers;

Figure 3 is a perspective detail view of the upper portion of the fliers and the blocks slidable thereon which operate the drop rods;

Figure 4 is an isometric view of one of the sliding blocks which are adapted to operate on the fliers as shown in Figure 3;

Figure 5 is a sectional plan view taken along line 5—5 in Figure 1;

Figure 6 is a vertical sectional view taken along the line 6—6 in Figure 5;

Figure 7 is an exploded isometric view of one of the brackets and its associated parts which are adapted to operate the stop motion mechanism;

Figure 8 is an exploded isometric view of the lug and ring which are adapted to be operated by the mechanism shown in Figure 7;

Figure 9 is an assembled detail plan view of the members shown in the Figures 7 and 8 and

showing how the drop rod operates when a strand of thread is broken;

Figure 10 is a sectional plan view of a modified form of the invention and taken along the line 5—5 in Figure 1;

Figure 11 is a vertical sectional view taken along the line 11—11 in Figure 10;

Figure 12 is an exploded isometric view of the mechanism adapted to operate the stop motion mechanism which is shown in assembled form in Figures 10 and 13;

Figure 13 is an assembled detail plan view of the parts in Figure 12 showing the drop rod operating the mechanism after a strand of thread is broken;

Figure 14 is a sectional plan view of another modified form of the invention which is taken along the line 5—5 in Figure 1;

Figure 15 is a front elevation of Figure 14;

Figure 16 is a plan view of a modified form of the invention, with parts omitted, similar to Figure 2 and showing the strand guiding members and also showing diagrammatically the path of travel of the several fliers;

Figure 17 is a vertical sectional view taken along the line 17—17 in Figure 16;

Figure 18 is a perspective view, with parts omitted, showing the tripping mechanism as it is associated with one of the fliers.

Figure 19 is a top plan view of another form of the stop motion and showing the drop rods in section, it being apparent that this type can be used beneath the rotating framework or surrounding the same;

Figure 20 is a transverse sectional view taken along the line 20—20 in Figure 19;

Figure 21 is a transverse sectional view taken along the line 21—21 in Figure 19;

Figure 22 is an elevation of a modified form of a member on the fliers held in elevated position by strand tension;

Figure 23 is a view similar to Figure 22 but showing the position of parts upon failure of strand tension;

Figure 24 is an isometric view of still another form of a member on the fliers and which is held in elevated position by strand tension;

Figure 25 is an elevation, looking at the rear of Figure 24.

Referring more specifically to the drawings, the numeral 10 denotes the base plate of a braiding machine which has rising therefrom a plurality of supports 11 for the annular internal gear 12, while disposed concentrically of this support, projecting upwardly from base 10, is a cylindri-

cal shaft 13 attached to the base 10 by means of the annulus 14. Rotatably mounted in bearings 15 and 16, which are in turn supported by base member 10, is a main drive shaft 17 which has 5 fixedly secured on the end thereof a pulley 18 and has rotatably mounted on the end thereof an idler pulley 19. Fixedly secured on shaft 17 is a beveled gear 20 which in turn engages another beveled gear 21 which is also fixedly 10 mounted on vertically disposed shaft 22. Shaft 22 operates the braid receiving and feeding mechanism which is not shown on these drawings because it is not a part of this invention, but is fully shown in Patent Number 1,765,117 of June 17, 15 1930.

The left-hand end of the main drive shaft 17 as shown in Figure 5, has fixedly secured thereon another beveled gear 24 which in turn engages a bevel gear 25 fixedly secured on the hub of disk 26. This disk 26 is mounted for rotation on fixed shaft 13. Fixedly secured to shaft 13 above disk 26 is hub 27 of a large gear 28, which gear, as illustrated in Figure 1, meshes at all times with a plurality of smaller gears 29, the purpose of 20 which will presently appear. Attached to the shaft 13, and in fixed relation to the gear 28 is a limiting collar 30 which supports a rotary hub 31 of a spider and spacing member 32, which is provided with a plurality of ring supports 33, 25 one for each of the lower bobbin and flier carrying members 34.

Mounted for rotation in each of the bobbin carrying members 34 are sleeve members 36 which have secured on the upper end thereof a gear 37. 30 It is evident that when bevel gear 24 rotates, it meshes with bevel gear 25 and rotates disk 26; and the members 34, and the mechanism associated therewith, will also be rotated. This rotation of course will cause the gears 40 to be rotated since they mesh with a stationary ring gear 12. Gear 29 will likewise be rotated since this meshes with gear 28. This rotation will cause the lower fliers 41 to rotate in the manner shown in Figure 2, and also the upper fliers 42 will be caused to 35 rotate in the same manner.

Each of the lower fliers 41 has a bobbin of yarn 41a and each of the upper fliers 42 has a bobbin of yarn 42a from which the yarn is drawn when the machine is operating.

The structure thus far described is fully shown and described in said Patent 1,765,117 and it is with a structure of this type that our invention is adapted to be used. Disposed within the braiding machine are a plurality of vertically disposed shafts 43 around which are centered the lower bobbin and flier carriers such as denoted by numeral 34. In said patent the shafts 43 are solid. These are made tubular for the purpose of receiving a part of this invention.

A vertically disposed hole is drilled through the center of each shaft 43 and a drop rod 44 is slidably mounted therein. A lug 45 is fixedly secured to the upper end of rod 44 and lug 45 has arms 46 and 47 integral therewith as shown in Figures 1 and 3.

A suitable bracket 48 is secured to the upper portion of housing 50 by any suitable means such as a stud bolt 49 and this bracket is adapted to support one of the lugs or projections 46. The lower flier 41, as shown in Figure 3, as it is rotated, will barely miss the projection 47. It is the purpose of this invention to provide a suitable lug or block 52 on the fliers 41 and 42 which are held in elevated position above arm 47 as shown on flier 41 in Figure 3, by means of the

cord or thread 53, as it passes to the braid receiving and feeding mechanism shown in said patent.

It is evident that block 52 which is slidably mounted on flier 41, will not fall low enough to engage the projections 47 on lug 45 as long as the thread or strand 53 holds it in the position as shown. But when the thread 53 is broken, as shown in the left-hand portion of Figure 3, on flier 42, it is evident that the block 52 will fall until it engages the projections 55. In this position, as the flier 42 rotates, the block 52 will contact the arm 46 and cause the lug 45 and drop rod 44 to rotate until the projection 46 will no longer be supported by bracket 48. At this time the drop rod 44 and the parts associated therewith, will fall downwardly in the bore in shaft 43 and operate the stop motion mechanism which will be later described.

It is evident that regardless of which way the fliers 41 and 42 rotate that block 52 will engage either projection 46 or 47 if the thread breaks and allows the block to fall downwardly to a point where the arms 46 and 47 will be in the path of travel of either one of the fliers. By referring to Figure 2 the path of the upper flier 42 or the lower flier 41 can be clearly seen.

Secured to base member 10 are a plurality of vertically disposed brackets 60 by any suitable means such as stud bolts 63a, and on the upper end of these brackets is a suitable ring 61, said ring 61 being rotatably mounted on the upper side of bracket 60. Also secured to base member 10 are a plurality of brackets 62 which are secured to said member 10 by means of stud bolts 63. This bracket projects upwardly and is adapted to be bent over the upper side of a ring 61 in a manner shown in Figures 1 and 5, but the bracket 62 does not contact ring 61 at any time.

Bracket 62 has a slot 65 therein and in this slot a suitable dog member 66 is adapted to be pivoted by any suitable means such as a pin 67. Dog 66 has a projection or a smaller portion 66a integral therewith which projects outwardly and is adapted to be contacted by the lower end of rods 44 when a strand of thread breaks and allows one of the blocks 52, on either one of the fliers 41 or 42 to fall and to contact one of the arms 46 or 47. Figure 9 shows the position of this dog after one of the rods 44 has fallen and caused the portion 66a of dog 66 to be moved. 50 Dog 66 is adapted, when moved, to contact a bracket 68 which is adjustably secured on ring 61 by means of a screw 70 penetrating slot 69 and being embedded in ring 61. A suitable tension spring 71 is secured to ring 61 and also to 55 one of the brackets 60 which normally holds each of the brackets 68 against the dogs 66 at all times.

When one of the drop rods 44 drops, due to a broken thread, it, on account of rotation of the framework 13, engages the portion 66a of dog 66 and moves to the position shown in Figure 9, the ring 61 is caused to rotate a small amount. This rotation will cause the arm 73, which is secured to ring 61, to move in the same direction 65 and to operate the stop motion mechanism which comprises a member 75 which is pivoted as at 76. This member 75 has two arms 75a and 75b (see Figure 6). The arm 75b of member 75 is adapted to fit in a notch in horizontally disposed rod 78 and the other arm 75a is adapted to be contacted by bevel surface 73a of member 73.

A torsion spring 71 which is mounted around member 75 tends to press the arm 75b into the notch in a rod 78 at all times. The trip mech- 75

anism is supported by a bracket 76 which in turn is secured to the upper side of member 10. Rod 78 is slidably mounted in brackets 79 and 80 which are in turn supported by base member 10. Fixedly secured on rod 78 is a collar 81 and also confined between this collar 81 and bracket 80, on the rod 78, is a compression spring 82. The right-hand end of rod 78 is bent at a right angle and has secured thereto another bent rod 85 which is slidably mounted in bracket 86. This rod is adapted to partially encircle a belt 87 which is shown on fixed pulley 18. When any one of the drop rods 44 fall and contacts dog 66a and pushes it into the position shown in Figure 9, the bevel surface 73a contacts arm 75a of member 75 and causes the other arm 75b to become disengaged from the notch in the member 78.

The above described form of the invention will operate to stop the machine regardless of direction of rotation of the framework about fixed shaft 13.

At this time the compression spring 82 will force rod 78 to the left in Figure 5 and cause the belt 87 to be shifted from fixed pulley 18 to idler pulley 19, thereby stopping the machine. It is seen that by this method the shift of the belt 87 from one pulley to another is not abrupt, but gradual, due to the force exerted by the spring 82, thus gently stopping the machine.

In Figures 10 to 13 inclusive, a slightly modified form of the invention is shown, in which the ring 91 is fixedly secured on top of brackets 60. Ring 91 has a suitable groove therein in which another ring 92 is adapted to slide. The ring 92 has secured, as at 93, a suitable tension spring 94, the other end of spring 94 being secured to one of the supporting members 11. The tension applied to the inner ring 92 normally tends to pull the brackets 95 against the dogs 96, said dogs 96 being pivoted in bracket 97 by any suitable means such as a pin 98. The bracket 95 is adjustably mounted on inner ring 92 by means of screw 95a which penetrates slot 95b. The bracket 97 is secured to the ring 91 by any suitable means such as bolts 99 which threadably engage the ring 91 in holes 100. The dog 96 has an arm 102 integral therewith which is adapted to be engaged or contacted by drop rods 44 when a thread is broken and the rod is caused to fall. Figure 13 shows the position of this dog and also the inner ring 92 when the stop motion mechanism is being operated.

Fixedly secured to the ring 92 is a member 103 which has a beveled surface 103a. This beveled surface 103a is adapted to contact one end of trip mechanism 104 which has two arms integral therewith, namely, 104a and 104b. This trip mechanism 104 is mounted in bracket 108 which in turn is secured to base member 10. The arm 104a is contacted by beveled surface 103a and the other arm 104b is adapted to fit in a suitable notch in rod 106 and is held in this position by means of a torsion spring 105 which encircles the hub portion of member 104. Rod 106 is slidably mounted in brackets 111 and 112 and on rod 106 is fixedly secured a cuff 113. This cuff 113, together with bracket 112, is adapted to hold compression spring 114 on rod 106. When a thread is broken and the drop rod 44 causes member 103 to trip or push the rod 104 out of the notch in member 106 it is evident that the rod 106 will move to the left in Figure 10 and cause the member 85, which is secured on the right-hand end of rod 106, to engage the belt 87 and pull it from the fixed pulley 18 to the idler pulley 19. As stated in the main

form of the invention, this movement of belt 87 from one pulley to another is gradual, thus insuring that no damage will be done to the belt.

It might be stated that in this form, as well as in the preferred form, regardless of the direction in which the braiding machine is moving, the result will be the same, namely, the stop motion will be operated in the same manner. For example, referring to Figure 13, if the machine should be operated in the opposite direction from that shown by the arrow, the dog 96 would be pushed in the opposite direction by drop rod 44 and the portion of the dog nearest the observer, would engage bracket 95 and push it to approximately the position shown, instead of the portion farthest from the observer, engaging the bracket.

Figures 14 and 15 show another modified form of the invention in which the stop motion is operated when the machine is going in only one direction, namely, in a clockwise direction. This form of the machine is used when the shift of the belt from the fixed pulley to the idler pulley is desired to be instantaneous. In this form of the invention the brackets 60 have rotatably mounted on the upper end thereof a suitable ring 120. This ring has integral with the upper surface thereof, a plurality of shoulders 129a which are adapted to be engaged by the drop rods 44 when a strand of thread is broken and the drop rods are allowed to fall directly on top of ring 120. This ring also has a plurality of radially disposed pins 129b in the outer periphery thereof. The pins 129b engage the upper portion of the lever 121 which projects downwardly and is pivoted as at 122 to bracket 123, and bracket 123 is secured to the base member 10.

Pivotedly secured as at 124 is a horizontally disposed rod 125 which projects to the right in Figures 14 and 15 and is slidably mounted in bracket 126. This rod 125 also has a member 85 on the right-hand end thereof which engages belt 87 and it is evident that when one of the drop rods fall, that the rod is pushed to the left and the belt 87 is likewise shifted from fixed pulley 18 to the idler pulley 19. A suitable lever 123 is pivoted as at 129 to a bracket 130, said bracket 130 being secured to base member 10. This lever 123 projects upwardly and is pivoted as at 131 to rod 125 and the upper end thereof is adapted to be grasped by one's hand and pulled to the left when the machine is desired to be stopped by manual means.

In Figure 2 the fliers have been designated by the additional reference characters A to L inclusive for the sake of making clear the description of the method of operation. Here it is seen that fliers A, C, E, G, I and K are the ones provided with the bores therein in which the drop rods 44 are disposed. The fliers B, D, F, H, J and L do not have these bores and rods, as it is not necessary, for it is seen that arm 41 in flier A is engaged by the weight 52 on flier B and also the weight 52 on flier C. Also, the arm 46 in flier A is engaged by the weight 52 in fliers L and K. The weight in flier L engages arm 46 in flier A and also arm 41 in flier K. Likewise, the weight in flier K engages the arm 41 in the flier I as well as the arm 46 in flier A. The same is true as to the other fliers, as it is seen that the long thread carrying arms 41 do not engage the rod associated with its flier, but engage the rods associated with the adjacent rod-carrying fliers, while the short thread carrying arms 42 engage the rods on the proximate fliers. It is thus seen that when the failure of a strand oc-

5 curs in a flier it cannot rotate, through an arc of more than 240 degrees before the slideable member on its arm engages a drop rod to stop the machine.

10 5 Figures 16, 17 and 18 show a modified form of the invention which is particularly adapted to be used with machines which are already installed.

15 In the forms of invention shown in Figures 1, 3, 5, and 10 it is necessary to bore the vertical shafts 43 in order to insert the drop rods. This is a very convenient structure when the machine is being manufactured complete at the factory but in order to install a mechanism of this kind on a machine already operating, some difficulty 20 is encountered in removing these shafts and boring them. It is evident that by placing the rings up near the upper portion of the braiding machine and by providing pivoted members associated with the several fliers, that it will not 25 be necessary to bore the shafts and therefore a stop motion device can be installed on machines already in use without the necessity of dismantling the machines and boring the shafts for the insertion of the drop rods.

30 25 In the form shown in Figures 16 to 18 inclusive, the rings and the attachments secured thereto, are very similar to the form shown in Figures 10 to 13 inclusive. This mechanism is also adapted to stop the machine when a strand is broken regardless of the direction of rotation of the 35 braiding machine. In order to construct a stop motion of this type we have provided a tripping dog 140 which has vertical projections 141 and 142, said dog being secured as at 143 to the housing 50 of the braiding machine.

40 It can be seen by referring to Figures 16 and 17 that the projections 141 and 142 are normally out of the path of travel of the fliers 41 and 42 but when block 52, which is mounted on each 45 of the fliers and normally held in an elevated position by a strand, falls upon the breaking of the strand, one of the projections 141 and 142 will be in the path of this member and the tripping dog 140 will be partially revolved. This principle is very similar to the principle shown 50 in the preceding form but it should be noted that the dog 140 is not pivoted on the shaft 43 but is slightly removed from the shaft and is pivoted on the top of the housing 50. The tripping dog 140 has another upwardly projecting member 144 integral therewith and this member 55 144 is sharpened at its upper end, which sharpened portion supports a projection 145 which is integral with the member 146. Member 146 is slidably mounted on a vertically disposed rod 147 which is secured to the upper portion of housing 50. A compression spring 148 is confined above member 146 and around the rod 147 by means of a nut 149 and this spring normally holds the 60 projection 145 down and against the upper edge of member 144.

65 Member 146 has another downwardly projecting member 150 integral therewith, the lower end of which normally clears the stop motion mechanism associated with the ring when the braiding machine is rotating, but it is evident that when one of the strands 53 breaks and allows the block 52 to fall downwardly to a position shown in Figure 18 that the member 140 will be 70 rotated, which rotation will cause projection 144 to be moved from beneath the projection 145 and allow the member 146 and the projection 150 integral therewith, under pressure of spring 148, to fall downwardly.

75 75 By referring to Figure 17 it can be seen that

in the lowermost position of member 146 that projection 150 in its rotation will engage horizontally projecting portion 151 and operate the mechanism associated with the ring which will presently be described.

80 5 Projection 151 is integral with pivoted member 152, said member 152 being pivoted to bracket 153 as at 154. This member 152 is very similar to member 96 which has been previously described, and projection 151 is similar to projection 102. (See Figure 13.) Bracket 153 is secured to stationary ring 155 by any suitable means such as bolts or rivets 158 and mounted within ring 155 is another ring 156 which is similar in all respects to ring 92. An adjustable bracket 160 is 15 secured to the inner ring 156 by any suitable means such as a screw or bolt 161 penetrating slot 162.

16 10 When the projection 150 engages one of the arms 151 the member 152 will be slightly rotated 20 about pivot point 154 very much in the same manner shown in Figure 13 which will impart a slight rotation to the inner ring 156. Since the pivoted members 152 are normally held in contact with the vertical leg of bracket 160 by 25 any suitable means such as a spring 165 secured to the inner ring as at 166 and also secured to the framework 167 as at 169, the ring 166 will return to its normal position after rotation has been imparted to this ring and the machine has 30 been stopped. A member 170 is secured to inner ring 156 and this member has a beveled surface 170a which contacts arm 104a of the tripping mechanism. This mechanism is identical to that shown in Figure 10 and described in the preced- 35 ing description.

40 In Figures 19, 20 and 21 a slightly modified form of the lower portion of the stop motion is shown, this form of stop motion being adaptable for operation with the actuators in the position 40 shown in Figure 1 or with the actuators in the position shown in Figure 16, it being evident that the stop motion ring can be made large enough to encircle the structure as shown in Figure 16, or made small enough to go beneath the structure as shown in Figure 1.

45 In this form of the invention, instead of having the ring similar to the ring 120, shown in Figure 15, which only actuates the stop motion when the braiding machine is running in one direction, 50 a ring 175 is provided which will actuate the stop motion regardless of which direction the framework of the braiding machine is rotating. This ring 175 is mounted for sliding movement on suitable brackets 176 which in turn are secured to 55 uprights 177 which are secured at their lower ends to the base 10, not shown in this figure. The ring 175, instead of having the projections which have one side thereof sloping, such as shown by 120a, in Figure 14, have projections 178 with vertically 60 disposed sidewalls disposed radially therearound and spaced apart from each other, and when a drop rod 44 or 150, as the case may be, falls downwardly, it will be engaged by the next succeeding raised rib 178 to actuate the stop motion 65 mechanism.

70 On the outer circumference of ring 175 are a plurality of triangular projections 179 which have two sloping sides so as to actuate the stop motion mechanism regardless of the direction of travel 70 of ring 175. The stop motion mechanism is very similar to the structure shown, for example, in Figure 10, and only a portion thereof is shown.

75 We have a plate 180 suitably supported by the base plate, and some distance thereabove, and on 75

this base plate are mounted brackets 181 and 182 which rotatably support rod 183 similar in all respects to rod 106 in Figure 10, and a compression spring 184 surrounds this rod between the brackets 181 and 182, one end of the compression spring resting against the bracket 181, whereas, the other end of the compression spring 184 is confined by a collar 185 on shaft 183.

Rod 183, near the left hand end thereof in Figure 19, and on the upper side thereof, has a notch in which one end 186 of a bell crank lever is adapted to rest. This bell crank lever is pivoted on a bolt 187 disposed between upstanding portions 188 and 189 of a bracket 190 and a torsion spring 191, has one end thereof secured to portion 188 and the other end passes around the upwardly projecting leg 192 of the bell crank lever, the purpose of the torsion spring being to hold the parts in the position shown in Figures 19 and 20 and to prevent the belt shift from being operated.

The upstanding portion 192 of the bell crank lever has both sides thereof beveled to a point so that when any one of projections 179 engages these beveled surfaces it will push the portion 192 of the bell crank lever to the left in Figure 20 or towards the observer in Figure 19 and this will raise portion 183 of the bell crank lever out of the notch in the rod 183 and will allow compression spring 184 to actuate the belt shift and stop the machine which will be a gradual movement.

Any suitable form may be arranged for mounting the ring 175, Figure 21 showing a type of forked brackets 176 and the ring 175 having a circular projection 175a therearound which fits into these forks to slidably support the ring.

In Figures 22 to 25 inclusive, a slightly modified form of the member held in elevated position on the fliers by strand tension is shown. In the previous figures, the member 52 on the fliers 41 and 42, is shown heavy enough to fall by gravity to a position where it will engage the means for releasing the drop rods to allow them to fall and stop the machine. It is evident that the heavier these members 52 are, the more liable they are to be a detrimental influence on account of the centrifugal force, as the fliers are revolving and tend to throw the weights 52 outwardly. In the forms shown in Figures 22 to 25 inclusive, these members which are held in elevated position by strand tension, are very much lighter in weight than in the previous figures, and a spring is employed to move the members downwardly upon failure of strand tension. This enables the weight to be very much lighter because the spring acts to force it downwardly at all times.

In Figure 22 the flier 42 is shown as having a pair of holes therein as in the other forms, but projecting outwardly from the lower portion of the vertical portion of the flier, is a bracket 200 having a pin 201 therein on which is pivoted a light weight member 202 which has an eye-portion 203 through which the strand passes.

The other end of the member 202 most removed from the eye-portion 203, has secured thereto a tension spring 204 and the other end of the tension spring is secured to pin 205 and it is seen in Figure 22 that strand tension holds the member 202 in horizontal position and distends tension spring 204, but upon failure of the strand or strand tension, the member 202 will assume the position shown in Figure 23 and therefore engages the members 141 or 142 in Figure 18 or the members 46 and 47 in Figure 3 to stop the machine.

In Figures 24 and 25 another form is shown in which the fliers 42 or 41 have the light weight member 205a slidably mounted thereon and the strand 53 is adapted to pass through a hole and beneath the member 205a to hold it in elevated position as shown in the drawings.

The flier 42 has projecting therefrom ears 206 and 207 which are penetrated by pins 208 and 209 which serve as guides for compression springs 210 and 211, the upper ends of the springs fitting against the projections 206 and 207 and the lower ends of the springs fitting against the member 205a and normally forcing it downwardly but the strand tension holds it in elevated position but upon failure of strand tension or failure of a strand, the member 205a will be forced downwardly by springs 210 and 211 until it occupies a position against the horizontal portion of the flier 41 or 42, as the case may be, and therefore will be in the path of the projections 141 and 142 in Figure 18 or the projections 46 and 47 in Figure 3, depending upon which type of apparatus is employed in the machine proper.

It is thus seen that a very light weight member can be employed which will not affect the flier 25 on account of centrifugal force, and yet the springs will force this light weight member downwardly upon failure of a strand or upon failure of strand tension to stop the machine.

In the drawings and specification there has 30 been set forth preferred embodiments of the invention, and although specific terms are used, they are employed in a generic and descriptive sense only and not for purposes of limitation, the scope of the invention being set forth in the 35 appended claims.

We claim:

1. In a braiding machine having a base and a rotating framework mounted thereon, a plurality of revolving fliers disposed around the periphery 40 of the framework, at least some of the said fliers having a drop member associated therewith, means integral with said drop member and supported by said framework for normally holding said drop members in elevated position, a stop 45 motion device located beneath said drop members, means carried by said fliers and held in elevated position by a strand and engaging said drop members upon the exhaustion of, or parting of a strand, to remove the drop member from its 50 support and allow it to fall to engage and operate said stop motion device, said stop motion device comprising a plurality of fixed supports mounted on said base, a ring member slidably mounted on said fixed supports, an arm secured 55 to said ring member, a plurality of brackets adjustably mounted on said ring member, a trip mechanism normally contacting said arm and secured to said base member, a second set of brackets fixedly secured to said base member and 60 having pivoted means mounted therein normally engaging said adjustably mounted brackets, said pivoted means being engageable by said drop member when a strand parts to impart rotation to said arm and ring to operate said trip mechanism.

2. In a braiding machine having a plurality of rotary fliers adapted to receive a strand of braiding material as it is fed to the braiding mechanism, a slidable member mounted on each of 70 said fliers and held in elevated position by said braiding material, an actuating member associated with at least some of said fliers, supporting means for holding said actuating members in elevated position, a stop motion device normally cut 75

of engagement with said actuating members, projections on said actuating members normally out of the path of travel of the adjacent fliers but disposed within the path of travel of said slidable members when said slidable members are allowed to fall upon exhaustion of braiding material to remove said actuating member from said supporting member and allowing it to fall to engage said stop motion device.

10. 3. In a braiding machine provided with a plurality of rotary fliers each adapted to receive a strand of braiding material as it is fed to the braiding mechanism, a slidable member confined on each of said fliers and adapted to have vertical 15 sliding movement thereon, said member being normally held in elevated position by said strands, an actuating member mounted concentrically of alternate fliers, supporting means for holding said actuating members in elevated position, a stop motion device normally out of engagement with said actuating members, tripping means integral with the upper end of said actuating members normally out of the path of travel of adjacent fliers but disposed within the path of 20 travel of said slidable members when said slidable members are allowed to fall upon exhaustion of material or parting of a strand, to actuate said tripping means to allow said actuating member to fall and engage and operate said stop motion 25 device.

4. In a braiding machine having a base member, a rotating framework, and a plurality of rotary fliers mounted in said framework, a drop member associated with the fliers, means on said fliers for operating said drop members when a strand parts, a slidably mounted ring member, a base for holding said ring member, a plurality of adjustable brackets secured to said ring member, a fixed arm secured to said ring member, a trip mechanism movable by said arm, a second set of 35 brackets fixedly secured to said base and having pivoted means mounted therein normally engaging said adjustably mounted brackets, said means being engageable by said drop members 40 when a strand parts to impart rotation to said arm and ring to operate said trip mechanism.

5. In a braiding machine having a base, a rotating framework mounted on said base and a plurality of fliers mounted in said framework, a stop motion mechanism, an actuator associated with some of said fliers, means on said fliers normally held in inoperative position by a strand tension for operating said actuator upon failure of strand tension, a fixed ring member, a second ring member slidably mounted in said first ring member, a fixed arm secured to said second ring member and a trip mechanism operable by said arm, a plurality of brackets fixedly secured to said first named ring member and having pivoted 50 means mounted therein, a plurality of brackets adjustably secured to said second ring member and engageable by said pivoted means, said pivoted means being engageable by one of said actuators upon failure of strand tension to impart rotation to said arm and second ring to operate said trip mechanism.

6. In a braiding machine having a base member, a rotating framework and a plurality of fliers rotatably mounted in said framework, an actuator associated with some of said fliers, means on said fliers normally held in inoperative position by a strand for operating said actuators in the absence of said strand, a rotatably mounted ring having notches in the upper side thereof and disposed 70 below said actuators and normally out of engage-

ment with the lower end of said actuators, a belt shift pivotally secured to said base member and means integral with said ring for positively operating said belt shift when a strand parts and causes an actuator to engage one of said notches. 5

7. In a braiding machine having a base member, a rotating framework and a plurality of fliers rotatably mounted in said framework and having means for receiving a strand, an actuator associated with some of said fliers, means on said fliers held in elevated position by a strand for operating said drop rods when a strand parts, a ring member slidably supported by said base and means for holding said ring member in one position, a plurality of brackets adjustably secured to said ring member, a fixed arm secured to said ring member, and a trip mechanism engageable by said arm, a second set of brackets fixedly secured to said base member and having pivoted means mounted therein normally engaging said adjustably mounted brackets, said pivoted means being engageable with said actuators when a strand parts to impart rotation to said ring and arm to operate said trip mechanism and a belt shift pivotally secured to said base member, and being normally held in inoperative position by said trip mechanism. 10 15 20 25

8. A braiding machine having a rotatable framework, a plurality of packages of yarn disposed on the framework, a plurality of fliers mounted on the framework and means for rotating the fliers around the packages of yarn while the framework is rotating, a slidable member mounted on each flier, means on the fliers for receiving the strands to hold the member in elevated position, stop motion means, a vertically slidable member mounted on the framework and having its lower end normally held out of engagement with the stop motion means, the member held in elevated position by the strand being movable by gravity by parting of a strand to engage said member and move it out of normal position to allow it to fall by gravity to engage said stop motion means to stop the machine. 30 35 40 45

9. A braiding machine having a revolving framework having a plurality of packages of yarn disposed thereon and a plurality of fliers mounted on the framework for rotation around the packages of yarn as the framework revolves, a member held in elevated position on the fliers by a strand passing therethrough, a plurality of drop members mounted on the framework and means for holding the drop members in elevated position, the members on the fliers in the absence of a strand in the fliers falling by gravity to release said drop members for falling, and means operable by the fallen drop members for stopping the revolving framework. 50 55 60

10. A braiding machine having a revolving framework having a plurality of packages of yarn disposed thereon and a plurality of fliers mounted on the framework for rotation around the packages of yarn as the framework revolves, a member held in elevated position on the fliers by a strand passing therethrough, a plurality of drop members mounted on the framework and means for holding the drop members in elevated position, the members on the fliers in the absence of a strand in the fliers falling by gravity to release said drop members for falling, and means operable by the fallen drop members for stopping the revolving framework, comprising an annular member mounted for rotation about the same center as the revolving framework and movable by a fallen drop member, and means operable by 70 75 80 85 90 95

the annular member for stopping the framework from revolving.

11. Stop motion means for a braiding machine comprising a vertically sliding rod mounted concentrically of alternate fliers, means for supporting the rods in elevated position, a weight on each flier held in elevated position by the strand passing through the flier, means on the rod engageable by the members on the fliers moving about the proximate rods as a center and by the weights on the proximate fliers for moving the rod from its supporting means and allowing it to move downwardly and means engageable by the lower ends of the rods when in lowered position for stopping the mechanism.

12. In a braiding machine having a rotating framework having a plurality of packages of yarn disposed thereon, a plurality of fliers mounted for rotation around the packages of yarn and disposed around the periphery of the framework and equidistantly spaced from the center of the framework, an axial support for each flyer, each of said supports having a centrally disposed bore therein, a vertically slidable rod mounted in each of said bores, means for normally holding the rods in elevated position, a movable member mounted on each flier and held in elevated position by the tension of a strand passing therethrough, the movable member engaging the rod upon failure of the strand tension to move the rod to allow it to fall in its bore, and means disposed below the rotating framework and engageable by the lower end of the fallen rod to stop the machine.

13. In a braiding machine having a plurality of fliers, a stop motion mechanism comprising a member movably supported on each of the fliers by a strand passing through the fliers, a vertically slidable rod and means for normally supporting the rod in elevated position, rotatable means disposed below the lower end of the rod and normally held in stationary position out of contact with the rod, means on the upper end of the rod engageable by the members supported on the fliers in the absence of a strand in a flier to move the rod from its support and to allow it to fall and engage and operate the rotatable means to stop the machine.

14. A braiding machine having a rotatable framework, a plurality of fliers mounted on the framework and means for rotating the fliers while the framework is rotating, a movable member mounted on each flier and held in one position by the strand carried by the flier, stop motion means disposed below the framework, a vertically slid- able rod disposed concentrically of at least some of the fliers and having means thereon for holding it out of contact with the stop motion means, the means held by the strand on the fliers in the absence of a strand being engageable with the means for holding the rod out of contact with the stop motion means to move the rod to cause it to engage the stop motion means to move the same to stop the machine.

15. In a braiding machine having a rotating framework, a base member for supporting the rotating framework, a plurality of rotating fliers mounted on the framework, at least some of the fliers having stop motion actuating means thereon, means for normally forcing said stop motion actuating means downwardly, means for normally holding said stop motion actuating means in elevated position, a stop motion mechanism, means carried by said fliers and normally held in elevated position by a strand and slidale downward upon

exhaustion of a strand for engaging the stop motion actuating means to remove it from its support to permit the means for normally forcing it downwardly to move it into engagement with the stop motion mechanism.

16. In a braiding machine having a rotary framework and a plurality of rotary fliers mounted in the framework, and having means for receiving a strand therethrough, a vertically slideable member mounted on each of the fliers and held in elevated position by a strand passing through the flier, an actuating member associated with each flier and means for moving the actuating member, a support for each actuating member, normally preventing movement of the actuating member, a stop motion mechanism operable by the actuating member, the slideable member on the flier upon lessening of the strand tension therein falling downward to engage and move the actuating member into engagement with the stop motion mechanism.

17. A braiding machine having a rotary framework, a plurality of packages of yarn disposed on the framework, a plurality of rotary bobbin fliers mounted on the framework for rotation around the packages of yarn, an annular member mounted for rotation about the same center as the said framework, driving means for the rotary framework, shifting means for connecting and disconnecting the driving means to and from the framework, means normally pressing the shifting means to disconnecting position, means for holding the shifting means in connecting position, means on the fliers held normally in elevated position by the strands passing therethrough, and means operable by means on said means on the fliers upon parting of a strand for engaging said annular member to release the holding means for the shifting means to stop the machine.

18. In a braiding machine having a rotating framework and a plurality of fliers mounted for rotation in the framework and being disposed around the periphery of the framework, some of the said fliers having a vertically and centrally disposed bore therein, a drop rod mounted in each of said bores, cooperating means on the rods and the fliers for normally holding the rod in elevated position, a movable member disposed below the framework and having projections thereon, said movable member normally maintaining a position of rest, thread carrying means on the fliers, a slideable member mounted on the thread carrying means and held in a raised position by a strand passing through the thread carrying members, the slideable member, when allowed to fall, by the absence of strand tension in the thread carrying member, engaging said cooperating means associated with another flier to allow the rod to fall to engage said movable member, and means operable by said movable member for stopping the machine.

19. In a braiding machine having a rotating framework and a plurality of rotating fliers disposed around the periphery of the framework, an axial support for each of the fliers, supports for alternate fliers having a vertically and centrally disposed bore therein, a drop rod disposed within each of said bores, a support on the flier frame and means on the rods engaging said supports for normally holding the rods in elevated position, a thread carrying arm for each flier, a member slidably mounted on each thread carrying arm and held in elevated position by a strand passing therethrough, the member on the

thread carrying arm of adjacent fliers, when allowed to fall by absence of yarn tension, engaging the means on the rod to remove it from its support, and stop motion means disposed below the framework and engageable by a fallen rod to stop the machine.

20. A braiding machine having a revolving framework supporting a plurality of yarn packages and fliers mounted for rotation around the 10 yarn packages, means for driving said revolving framework, means for normally holding the driving means in connection with the revolving framework, a plurality of vertically movable members supported on the framework and normally held in elevated position, means operable 15 upon a lessening of strand tension for tripping said vertically movable members and allowing the same to move downwardly, a normally stationary annular member disposed concentrically 20 of the revolving framework, fixed means associated with said annular member, a plurality of pivoted means associated with said annular member and said fixed means, but disconnected from the annular member, and movable by a fallen 25 vertically movable member for moving said annular member to move the driving means out of connection with the revolving framework.

21. A braiding machine having a revolving framework supporting a plurality of yarn packages and fliers mounted for rotation around the 30 yarn packages, means for driving said revolving framework, means for normally holding the driving means in connection with the revolving framework, a plurality of vertically movable members supported on the framework and normally held in elevated position, means operable 35 upon a lessening of strand tension for tripping said vertically movable members to cause the same to move to lowered position, an annular member disposed concentrically of the framework 40

and movable by a fallen vertically movable member and means controlled by movement of the annular member for disconnecting the driving means from the framework.

22. In a braiding machine, a revolving framework, 5 a plurality of drop rods disposed on the framework, means for normally holding the drop rods in elevated position, means controlled by the tension of the yarn in the braiding machine for actuating said drop rods to allow them 10 to fall, a normally stationary annular member disposed concentrically of the revolving framework, means for driving the framework, means controlled by the annular member for normally holding the driving means connected to the 15 revolving framework, and pivoted means disconnected from the annular member movable by a fallen drop rod for moving the annular member for moving the driving means to disconnected position with relation to the said framework. 20

23. In a braiding machine having a revolving framework, means for driving the framework, means for normally holding the driving means in connection with the revolving framework, a plurality of drop members on said framework 25 normally held in elevated position, means operable upon lessening of strand tension for causing at least one of said drop members to fall to lowered position, a movable annular member disposed concentrically of the revolving framework, 30 stationary means supporting the annular member, a plurality of members pivotally supported by said stationary means and engaging said annular member and movable by a lowered drop member for moving the annular member and 35 means movable by said annular member for disconnecting the driving means from said revolving framework.
